(57) **CLAIM**

The ornamental design for a utility meter, as shown and described.

DESCRIPTION

FIG. 1 is a front view of a utility meter;

FIG. 2 is a front perspective view of the utility meter of FIG. 1;

FIG. 3 is a top view of the utility meter of FIG. 1;

FIG. 4 is a side view of the utility meter of FIG. 1;

FIG. 5 is the opposing side view of the utility meter of FIG. 1;

FIG. 6 is a rear view of the utility meter of FIG. 1;

FIG. 7 is a bottom view of the utility meter of FIG. 1;

FIG. 8 is front view of another embodiment of a utility meter;

FIG. 9 is a front perspective view of the utility meter of FIG. 8;

FIG. 10 is a top view of the utility meter of FIG. 8;

FIG. 11 is a side view of the utility meter of FIG. 8;

FIG. 12 is the opposing side view of the utility meter of FIG. 8;

FIG. 13 is a rear view of the utility meter of FIG. 8;

FIG. 14 is a bottom view of the utility meter of FIG. 8;

FIG. 15 is front view of yet another embodiment of a utility meter;

FIG. 16 is a front perspective view of the utility meter of FIG. 15;

FIG. 17 is a top view of the utility meter of FIG. 15;

FIG. 18 is a side view of the utility meter of FIG. 15;

FIG. 19 is the opposing side view of the utility meter of FIG. 15;

FIG. 20 is a rear view of the utility meter of FIG. 15; and,

FIG. 21 is a bottom view of the utility meter of FIG. 15.

The objects shown in broken, phantom lines are shown for environmental purposes only and form no part of the claimed design.
